UNITED STATES PATENT OFFICE

153,305

DESIGN FOR A SWITCH BOX COVER

Ray Patten, Norwalk, and Arthur N. Bec Var,
Bridgeport, Conn., assignors, by mesne assignments,
to The Trumbull Electric Manufacturing Company, a corporation of Connecticut

Application March 29, 1947, Serial No. 138,036

Term of patent 14 years

(Cl. D26—13)

To all whom it may concern:

Be it known that we, Ray Patten and Arthur N. Bec Var, citizens of the United States, residing respectively at Norwalk, in the county of Fairfield, State of Connecticut, and Bridgeport, in the county of Fairfield, State of Connecticut, have invented a new, original, and ornamental Design for a Switch Box Cover, of which the following is a specification, reference being had to the accompanying drawing, forming a part thereof.

In the drawing showing our new design for a switch box cover, Fig. 1 is a front elevation; Fig. 2 is a side elevation; and Fig. 3 is an end view.

We claim:

The ornamental design for a switch box cover, as shown.

RAY PATTEN.
ARTHUR N. BEC VAR.
